UNITED STATES PATENT OFFICE.

WILLIAM HOCHHAUSEN, OF BROOKLYN, NEW YORK.

ELECTRIC-ARC LAMP.

SPECIFICATION forming part of Letters Patent No. 605,228, dated June 7, 1898.

Application filed January 22, 1897. Serial No. 620,222. (No model.)

To all whom it may concern:

Be it known that I, WILLIAM HOCHHAUSEN, a citizen of the United States, and a resident of Brooklyn, in the county of Kings and State 5 of New York, have invented a certain new and useful Improved Arc-Lamp, of which the following is a specification.

This invention relates to electric-arc lamps, and particularly to that class of arc-lamps 10 wherein both carbons are moved and the arc is maintained at a fixed spot.

The invention has for one of its objects a construction whereby an exceedingly even and positive feeding of the carbons may be 15 produced and the feeding mechanism guarded against destruction by abnormal strength of current and whereby the lamp may be completely shunted when the carbons have burned to their full extent.

Another object is to so proportion and associate the parts of a lamp that long carbons 20 may be used without increasing the length of the lamp as a whole.

Another object is to so construct the lamp 25 as to facilitate to the utmost the trimming thereof and globe-cleaning and to provide for recarboning the lamp without exposing the controlling mechanism.

With these objects in view the invention 30 consists in the construction, combination, and arrangement of parts hereinafter fully described, and set forth in the claims.

In the accompanying drawings, which form a part of this specification, Figure 1 represents the improved lamp in side elevation. 35 Fig. 2 is an elevation of the upper portion of the lamp with the casing and globe removed. Fig. 2^a is a horizontal section through the lamp in the plane indicated by line *a a*, Fig. 40 2, in which the magnets and dash-pot are diagrammatically represented. Fig. 3 is another side elevation of the same part of the lamp. Fig. 4 is a plan of the lamp with the cap removed. Fig. 5 is a transverse vertical section 45 of the upper portion of the lamp mechanism, taken on the line 5 5 of Fig. 4. Fig. 6 is a longitudinal central section through the clutch mechanism. Fig. 7 is a view in perspective of the step-by-step feeding mechanism. Fig. 8 is a diagrammatic representation 50 of the circuits of the lamp. Fig. 9 is a horizontal sectional view of one of the terminal

clamps. Fig. 10 is a vertical section through the ash-pan and the hinge for the same.

A indicates the jacket inclosing the controlling and feeding mechanism of the lamp. 55

B indicates the globe, and C the ash-pan.

The "lamp-frame," as it may be termed, 60 consists of the base-plate 11, surmounted by the ring 12, and the angular column 13, upon the top of which is constructed a chamber consisting of the ring 14 and the cap 15, the suspension-pulley 16 for the lamp being mounted in lugs formed integral with the cap. 65 The column 13 divides the upper portion of the lamp into two chambers. The one contains the upper-carbon holder 17 and is accessible from the exterior by means of the door 18, formed in casing A, and a supplemental door 19, formed in the ring 12, as seen 70 in Figs. 1 and 2. These doors may be constructed in any suitable way, the door 18 being shown as connected by strap-hinges to the casing A and closed by means of catches 20, pivoted to the door and engaging with 75 buttons upon the body of the casing, while the door 19 is shown as hinged to the base 11 and is held in closed position by the engagement therewith of the door 18. By this means 80 the upper-carbon holder is made accessible without the necessity of exposing any of the other mechanism of the lamp.

The vertical way for the carbon-holder 17 85 may be constructed within the angular chamber or column 13 in any suitable manner. In the present instance such way is formed by means of strips 21, secured to the inner walls of said column. From the upper-carbon holder there extends a flexible connection, as the chain 22, up into the upper 90 chamber of the lamp formed by parts 14 and 15, where it passes over a suitable roll or pulley, such as chain-wheel 23, and down at the back of column 13, where it is connected to the lower-carbon-carrying rod 24. This 95 carbon-carrying rod passes through a suitable guide located in the base 11 and through a similar guide 25, provided with antifriction-rollers and mounted on a bracket 26, depending from the base 11. 100

As seen in Fig. 3, the bracket 26 passes through an opening in the base 11, and has a plate at its upper end, by which it is secured to the base of the lamp and upon which is

mounted the first-mentioned guide 27. It will be noticed that this bracket, as well as the column 13, are insulated from the base 11, as indicated in Fig. 3. The lower end of the 5 carbon-carrying rod 24 is curved at right angles to its main portion and carries the carbon-holder 28, which may be of any suitable construction. Attached to the lower part of bracket 26 is a ring 29 for guiding the lower 10 carbon. To insure a better electrical connection between the rod 24 and the carbon-holder 25, a conductor, as 30, has its ends connected to said parts, respectively.

In this lamp separate magnetic devices are 15 provided for striking the arc and for feeding the carbons. The magnet for striking the arc is indicated at 31 and may be of any suitable form, but by preference consists of an iron-clad solenoid-magnet the core of which is 20 connected at its upper end by the link 32 to one end of the weighted frame 33, while the lower end, on which is mounted the armature 34, is connected to the lever 35, pivoted upon a bracket, as 36, attached for convenience 25 sake to the sheath of the magnet 31. The other end of the lever 35 is connected to the piston of the dash-pot 37. The piston of the dash-pot is of the usual construction; but the upper end of the dash-pot has formed therein 30 an opening by which the dash-pot is movably seated upon the valve-shaped end 38 of the post supporting the dash-pot. By this means the piston may return very quickly, as it may raise the dash-pot off said valve 38 and so 35 quickly expel the air, and as the piston descends the valve will close the opening and cause said descent to be very gradual.

The weighted frame 33 is mounted upon trunnion-screws 39, which pass through posts 40, arising from the plate 41, which constitutes the floor of the upper chamber. In the projecting ends of the weighted frame is journaled a shaft 42, upon which is rigidly mounted the chain-wheel 23. Upon this shaft, at 45 the side of the chain-wheel 23, is idly mounted a sleeve which carries a worm-wheel 43 and a clutch member 44, which clutch member engages with a corresponding member 45, formed upon or secured to the side of the 50 chain-wheel. The shaft 42 is movable longitudinally in its bearings, as indicated in Figs. 4 and 6, and the sleeve 43 is held against longitudinal movement by a plate 46, secured to the frame 33 and taking into a groove formed 55 upon the end of the sleeve, as indicated at 47 in Fig. 6. By the movement of the shaft 42 the clutch members are thrown into and out of engagement. This shifting of the shaft 42 is accomplished as the weight 33 moves up 60 and down in response to the action of the magnet 31. One form of mechanism that may be used for causing this longitudinal movement consists of a spring 48, mounted upon the weighted frame and bearing against the 65 end of shaft 42, as seen in Figs. 4 and 6. This spring tends to throw the clutch members into engagement. Said members are thrown

out of engagement by means of the triangular lever 49, which is pivoted to a lug upon the frame 33 and bears at its upper end against 70 the end of the shaft 42, while its lower angle rests upon a suitable stop, as screw 50, which rises from the plate 41. It will be seen then that as the projecting ends of the weighted frame carrying the shaft 42 are raised the 75 spring 48 will force the clutch members into engagement and as said ends are depressed the triangular lever will force the shaft 42 against the action of said spring and disengage the members of the clutch. The mechanism just described is that which strikes the arc, the detail operation of which will be given 80 farther on.

I will now describe the feeding mechanism. The worm-wheel 43 engages with a worm 51, 85 which, as seen in Fig. 5, is mounted in bearings in a strip 52, extending across the post 40 and in a step located upon the plate 41. The construction and location of the worm-wheel and worm are such that their engagement is in the vertical plane through the axis 90 of the tilting frame 23. Therefore the movement of the frame in striking the arc does not separate these parts of the gear nor in any way affect their continuous working engagement. Upon the lower end of the worm-shaft is mounted a ratchet-wheel 53. For operating this ratchet-wheel the electromagnets 54 are provided. (See Figs. 3, 7, and 8.) These magnets have extended pole-pieces, 95 as indicated, between which is located an armature 55, which is mounted upon a shaft 56, turning in bearings in the strap 57 and the connecting-strip 58. Upon the upper end of the shaft 56 is mounted an arm 58, in 100 which is pivoted the pawl 59, which pawl engages with the ratchet 53 for rotating it. To the rear end of the pawl 59 is connected a spring 60, Figs. 4 and 7, by means of the link 61. This spring 60 may be of any suitable 105 form and mounted in any desired manner, but, as here shown, is supported upon a post rising from the plate 41, Fig. 4, and has a tension-screw 62 bearing thereagainst. A detent co-operating with the pawl 59 is shown at 110 63, Fig. 5. Upon the arm 58 is mounted a contact-spring 64, which engages with a contact-point 65, mounted on an insulated post which 115 is in circuit with the magnets 54. As the magnets 54 are energized the armature 55 is drawn into right line with the poles thereof, which causes the arm 58 to swing and the pawl 59 to rotate the ratchet-wheel. As the armature completes its swing it carries the contact-spring 64 out of engagement with the 120 contact-post 65 and so breaks the circuit through the magnets. Then the spring 60 forces the arm 58 back into its normal position, thereby carrying the armature out of 125 right line with the poles and places the mechanism in position to move the ratchet-wheel another stated distance. A spring-stop, as 66, is mounted in the path of the armature 55 to limit its return movement. Magnets 54 130

and the mechanism operated thereby constitute a vibrating or step-by-step motor. To reduce to the minimum the change in resistance in the coils of magnets 54, due to the heat 5 of the lamp, said coils are made from German-silver wire. By making these coils of German silver the lamp is caused to burn with a uniform length of arc, since the heating of the coils will not affect the flow of current 10 through them and the feed will always take place when the arc is lengthened to the predetermined or adjusted amount.

The lamp as represented is intended to run on a direct-current circuit, either constant 15 current or constant potential; but some features are useful in lamps run by alternating currents. The circuits of the lamp are indicated in Fig. 8. The positive terminal is shown connecting directly to the frame at the 20 post 67, whence circuit goes to flexible conductor 68, connected at one end to the angular column 13 and at the other end to the weight or upper-carbon holder 17, whence the current passes through the carbons and the 25 lower-carbon holder 24 to the flexible conductor 69, connected to the upper end of the lower-carbon holder and extending through the coil of the arc-striking magnet 31 to line, as at 70. This may be termed the "arc- 30 striking branch" or "arc-circuit" of the lamp.

The feeding-circuit is a shunt through magnets 54, which shunt starts from the frame, passes to the shaft 56, thence to the contact-spring 64, through the contact 65 and its supporting insulated post, to and through the coils of the magnet, and then over conductor 35 71 to the return.

A safety-shunt around magnets 54, which is normally open and automatically closed by 40 an abnormal strength of current flowing through said magnets, starts from the frame of the lamp, as at 72, extends to the armature-lever or cut-out magnet 73, and when said armature is drawn up by magnets 54 passes 45 across contact 74, thence through the coil of magnet 73 and the resistance 75, over conductor 76, to the return.

The cut-out just mentioned is illustrated in 50 Figs. 3 and 8 and consists of the magnet 73, suitably mounted upon the column 13 and having the elbow armature-lever 77, which serves as a supplemental armature to magnets 54 and as an armature for magnet 73. Attached to this double armature is a plate-spring 78, between which and the contact-spring 79, attached to the lower end of lever 77, projects a stop 80, against which spring 77 bears to return the contact-spring 79 from engagement with its coöperating contact, said 55 coöperating contact being insulated from all surrounding parts, as indicated in Fig. 3.

Another shunt-circuit is provided for short-circuiting the entire lamp mechanism when the carbons have burned their full extent. 60 This circuit is by way of the lamp-frame, over flexible conductor 68 and the upper-carbon holder, to an insulated projection 81, mounted

upon the frame of the lamp, as indicated in Figs. 2 and 8. From this projection the circuit is continued by way of conductor 82 to 70 the conductor 76, and thence to the return at 70.

The hand cut-out for use in trimming the lamp is mounted in the upper chamber of the lamp, and consists of a plate 83, mounted upon 75 the post arising from the frame of the lamp, as shown in Figs. 2 and 4, the plate 84 coöperating therewith and insulated from the frame of the lamp and from said plate and connected to the negative terminal of the lamp. These 80 plates 83 and 84 are placed side by side, as indicated in Fig. 4, and the pair of springs 85 is mounted upon the rock-shaft 86 and adapted to be forced in between springs 83 and 84 by the handle 87, mounted upon the 85 rock-shaft 86, exterior to the lamp, as seen in Figs. 1, 2, and 4. This rock-shaft for the sake of safety is divided by an insulating-coupling, as indicated at 88 in Fig. 4. When the springs 85 are forced into engagement with the plates 90 83 and 84, a direct shunt across the terminals of the lamp is formed.

The operation of the lamp may be briefly stated as follows: In the drawings the carbons are represented as having burned nearly 95 to their full extent. When the lamp is fresh trimmed, the weight 17 will be at the upper end of the triangular chamber and the lower-carbon holder will be at the lower end of the globe, and when the lamp is at rest the carbons will be together. Upon turning the current onto the lamp, magnet 31 will be energized, when it will attract its armature 34, thereby forcing up the outer end of the weighted frame 33, to which said armature is 105 attached. This will carry up the chain-wheel 23 and raise that portion of the chain connected to the upper-carbon holder, but it does not raise the other part of the chain—that connected to the lower-carbon holder—because the chain-wheel is so located in the weighted frame that its rear side is in alignment with the pivots 39 of said frame. As the frame is forced up shaft 42 is pressed by 110 spring 48 toward the sleeve, thereby throwing the clutch member 45 into engagement with its coöperating member 44. In this manner the worm-gear is coupled to the chain-wheel. Then the carbons being separated, sufficient current will flow through magnets 54 120 to bring its armature into right line with the poles thereof and through the ratchet mechanism rotate the worm. This will gradually feed the carbons together. As the armature approaches the right-line position in respect 125 to the poles the circuits of the magnet will be interrupted at the contacts 64 and 65, when spring 60 will return the armature to its normal position, thereby closing the circuit again through said magnets and allowing them to 130 operate the ratchet mechanism another step.

So long as the current is flowing through the lamp, magnet 31 will maintain the clutch members in engagement and the step-by-step

ratchet mechanism just described will produce a continuous feeding of the carbons. Should current of abnormal strength from any cause pass through the magnets 54, they will

- 5 attract the armature 77, thereby closing circuit through the coil 73, which will maintain the circuit closed through the safety-shunt until the equilibrium of the circuits is again obtained. This abnormal strength of current through magnets 54 being occasioned by an undue separation of the carbons will flow through the safety-shunt until magnet 31, on being weakened by the flow of current over said shunt, has allowed the carbons to approach each other, the resistance 75 being interposed in the safety-shunt to establish that relation of resistance between the safety-shunt and the arc-circuit which will allow the regular feeding of the lamp to be resumed.
- 20 Then in the regular operation of the lamp as the carbons burn out the cut-out shown will be closed between the contact 81 and the upper-carbon holder 17.

A few details in the construction of the less 25 essential features of the lamp will now be described.

In designing this lamp the intention was to place the parts to which frequent access is necessary in such position that they could be 30 reached without opening into the mechanism of the lamp. Such improvements in this line as facilitate the retrimming of the lamp have already been mentioned. Provision is also made for connecting and disconnecting the 35 lamp to the circuit-terminals without opening the lamp and at the same time providing for the location of these terminal connections within the casing. For this purpose there is mounted in the upper chamber of the lamp a 40 clamp-terminal, as indicated in Fig. 9, both at the positive side and at the negative side of the lamp. This terminal consists of a plate 89, folded upon itself and having mounted upon the folds a block or dog 90 and pivoted 45 to the plate, as at 91. Against one angle of this plate a screw, as 92, presses, said screw being mounted in a nut located between the folds of the plate, as at 93. A conductor, as 70, being inserted between the block 90 and the 50 folds of the plate 89, it only remains to turn the screw 92 to clamp said conductor in place. These screws 92 may be reached through suitable openings formed in the ring 14, as indicated in Figs. 2 and 4, the passage for the 55 terminals of the conductors being placed in alinement with notches formed in said ring, as indicated in Figs. 3 and 4.

A convenient means for attaching and detaching the globe B consists of forming upon 60 the base-plate 11 lugs, as 94, and forming upon the upper globe-ring 95 catch projections, as 96, which should be pointed at their ends for ready insertion between the lugs 94 and each provided with a notch, as indicated, 65 for securing a safe engagement between them and the lugs, as indicated in Fig. 3. To remove the globe, it is simply necessary to raise

it slightly and rotate it to the left for a short distance when it may be withdrawn from the base 11. It may be as readily inserted by the 70 reverse operation.

Another important improvement over lamps of similar construction now in the market consists in shortening the bracket supporting the guides for the lower carbon, so that it 75 shall be at a considerable distance above the lower end of the globe, as indicated in Fig. 1. This provides for ready access to the globe in wiping out the same, such access being had in the usual way through the opening at 80 the lower end of the globe by opening the ash-pan.

A convenient means for holding the ash-pan open and for holding it closed is also a 85 feature of this invention and is illustrated in Fig. 10. The ash-pan is hinged by an ear 97 in lugs projecting from the lower globe-ring, and this ear is notched, as indicated in Fig. 10. In a chamber 98, from which the hinged lugs project, is a spring-mounted detent 99, shaped to engage with notches in the ear 97. One of these notches is so located that the detent will hold the ash-pan up in place, and the other is so located that when the ash-pan is opened or turned out of the 95 way it will hold it in that position until forcibly closed.

The contact-plate 81, Figs. 2 and 8, has the conductor 82 connected to it by means of a binding-post 99, into which said conductor is 100 passed from the rear of column 13 through a suitable opening formed in said column.

The resistance 75 is by preference mounted upon porcelain supports 100, secured to the 105 column 13, as indicated in Fig. 3.

The shape and the combination of the various details above described and the arrangement of circuits within the lamp may be changed or modified without departing from the invention.

What I claim as my invention is—

1. In an arc-lamp, the casing containing the operating mechanism in combination with a vertical partition dividing the space inclosed by said casing into two chambers one of them 115 containing the mechanism to which access must be had in trimming, and means for gaining ready access to said chamber from the exterior without opening into the other chamber, substantially as set forth.

2. In the arc-lamp substantially as shown and described, the combination with the upper and lower ends or plates, of the chambered column 13, connecting them and the casing A extending from one plate to the other and provided with the door for closing the chamber in said column, as and for the purpose set forth.

3. The combination with the base-plate 11, and the top plate 14, suitably capped, of the chambered column joining said plates, the ring 12, provided with the door, and the casing extending from the ring 12, to the plate 14, and provided with a door which coöper-

ates with the aforesaid door to close the chamber in said column, as and for the purpose set forth.

4. The combination with the connected carbons, of the longitudinally-movable shaft from which they are suspended, a clutch member fixed upon said shaft, the coöperating clutch member sleeved upon the shaft, means for moving said shaft longitudinally to throw the clutch members together as the arc is struck, and an electric motor operated by the current of the lamp and geared to said sleeve, for the purpose set forth.

5. The combination with the pivoted frame, the longitudinally-movable shaft journaled thereon, the carbons operated from said shaft, a spring resting against one end of the shaft, a triangular lever pivoted to the frame and bearing against the other end of the shaft, means for tilting the frame and thereby causing longitudinal movement of the shaft, feeding mechanism for rotating the shaft, and a clutch device operated by said longitudinal movement to engage the shaft with the feeding mechanism, for the purpose set forth.

6. The combination with the arc-striking magnet 31, the feeding-magnets 54 and their armature, of a supplemental armature located out of the normal field of said feeding-magnets and operated thereby only under an abnormal strength of current through said magnets, a shunt around the feeding-magnets completed by the movement of said supplemental armature, and a magnet in said shunt for holding the armature in circuit-closing position, substantially as set forth.

7. The combination with the feeding-mag-

nets in a shunt from the arc-circuit, of the elbow-armature having one arm opposite the poles of the feeding-magnets to be attracted thereby under an abnormal strength of current through the shunt, a shunt around the feeding-magnet maintained normally open, a fixed contact, and a contact carried by said armature for closing said normally open shunt, and a magnet in circuit with said contacts and acting upon the other arm of said armature for holding them in engagement.

8. In an arc-lamp, the combination with the arc-circuit, of the feeding-magnet shunt, the normally open safety-shunt around the feeding-magnet, a resistance in said shunt so proportioned with relation to the arc-circuit as to insure the resumption of the regular feeding operation, and the automatic cut-out shunt for the lamp around the arc inclosing the feeding-magnet circuit and said resistance, substantially as set forth.

9. A terminal clamp consisting of a plate folded upon itself to receive a terminal wire in the fold, in combination with a triangular lever pivoted at one angle between said folds and bearing at an outer angle against an inserted terminal wire, and a screw mounted between the folds of the plate and bearing against the other outer angle of said lever, substantially as set forth.

Signed at New York, in the county of New York and State of New York, this 28th day of December, A. D. 1896.

WILLIAM HOCHHAUSEN.
